UNITED STATES PATENT OFFICE

HAROLD C. ST. DENNIS, OF SYRACUSE, NEW YORK

DRIVING FINGER FOR SURFACING MACHINES

Application filed May 30, 1930. Serial No. 457,648.

This invention relates to driving fingers for surfacing machines, and particularly to the driving fingers of machines used for surfacing lenses such as used by opticians.

It has been the conventional practice to use steel bars as driving fingers on surfacing machines for lenses. In operation, these machines are extremely noisy due to the clattering of the steel driving fingers against the steel arms of the block holders. This is particularly undesirable where a grinding machine, or a number of them, are used in a room close to a waiting room or office, as is very often the case. Various efforts have been made to quiet these machines, such as wrapping the driving fingers with tape, but such efforts have been unsuccessful; the tape wearing out in a few days.

In a machine using steel driving fingers, the wear of these fingers is extremely rapid. In many cases small microscopic articles of steel, worn from the driving fingers, come in contact with the lens surface and seriously scratch the same.

Steel fingers are built so that when one face becomes badly worn, the finger may be turned through ninety or one hundred eighty degrees, so as to bring a new face into position for driving. Even with this expedient, it is necessary where the surfacing machine is in constant use, to replace the driving fingers after a comparatively few weeks. Since only a portion of the upper part of a driving finger is worn out, unnecessary expense is entailed in replacing the entire member. Removal of worn driving fingers and their replacement with new ones consumes some little time which often can not be well spared in a busy shop.

When the driving fingers of a lens surfacing machine become badly worn, the accuracy of the machine for lens grinding is often seriously impaired.

An object of this invention is to provide an improved driving finger for surfacing machines, and particularly lens surfacing machines, which will be quiet in operation. A further object is to provide a driving finger having a body portion of sufficient rigidity for driving purposes, and a bearing face,

mounted on the body portion, of softer material better adapted for bearing contact than the material of the body portion.

A further object of the invention is to provide a driving finger having a bearing face which may be replaced when worn without requiring replacement of the entire driving finger. A further object is to provide a driving finger having a wearing surface of such material that it is impossible for small hard particles to be displaced therefrom with the danger of causing scratching of the lens.

A further object of the invention is to provide a driving finger having a replaceable bearing face which may be removed or inserted without dismantling the machine, or removing the driving fingers from their operative position.

Other objects and advantages will be pointed out and will become apparent as the description proceeds.

The invention consists in the novel features and in the combinations and constructions hereinafter set forth and claimed.

In describing this invention, reference is had to the accompanying drawing, in which like characters designate corresponding parts in all the views.

Figure 1 is a perspective view of a lens surfacing machine to which my improved driving fingers are applied.

Figure 2 is a front elevation of my improved driving finger.

Figure 3 is a side elevation of the driving finger illustrated in Figure 2.

Figure 4 is a front elevation of a driving finger showing my invention applied thereto in a modified form.

Figure 5 is a side elevation of the driving finger illustrated in Figure 4.

Figure 6 is an elevation showing a detailed view of the means for mounting the driving fingers.

Figure 1 illustrates an automatic surfacing machine of the conventional type used for lens grinding. A torque or cylinder attachment 10 is driven by suitable operating mechanism. A block 11 is mounted on the cylinder attachment and the lens to be surfaced is secured to a lens block holder 12 which holds

the lens in contact with the block 11 to surface it with the proper contour in a manner which will be well understood by those skilled in the art.

5 The lens block holder 12 is provided with arms 13 which extend between driving fingers 14. The driving fingers 14 are secured by suitable means, such as a clamping screw 15, to the cylinder attachment. Thus, the oscillating rotary motion of the cylinder attachment 10 will be imparted through the driving fingers 14, and arms 13, to the lens block holder 12 on which the lens is mounted.

10 A throw crank 20 and crank pin 21 cooperate with the arms 13 to give the lens block holder 12 the necessary composite sliding action on the block 11. This feature of the drive is well known to those learned with lens surfacing machines, forms no part of the 15 present invention, and a detailed description of it is unnecessary.

15 When the cylinder attachment 10 oscillates in a clockwise direction, the arms 13 will be driven by the left hand driving fingers. 20 When the cylinder attachment oscillates in a counter-clockwise direction, the arms 13 will be driven by the left hand driving fingers. To allow perfect freedom of motion of the arms 13 between the driving fingers 14 it is necessary that some play be provided. Due to this play there is necessarily a certain amount of clattering between the arms 13 and driving fingers 14.

25 Referring to Figures 2 and 3, the driving finger 14 is provided with a cut-out portion into which a bearing face 25 is inserted. This bearing face preferably forms a flush surface with the body portion of the driving finger as shown in the drawing, though this is not necessary. The bearing surface 25 is secured to the driving finger 14 by any suitable means, and in the form of the invention shown in Figures 2 and 3, by counter-sunk screws 26.

30 The bearing surface may be made of any 45 suitable material. I prefer to use tough rubber or leather, or composite materials having similar properties. Good results however, can be obtained with other materials such as fiber board.

35 The modification of the invention shown in Figures 4 and 5 provide means whereby the bearing surface may be replaced without removing the driving fingers from operated position. The construction of the driving finger is identical with that described in connection with Figures 2 and 3. The bearing face however, instead of being secured in place by screw means, is held in place by a cap 27 which fits over the end of the driving 40 finger.

45 The cap 27 extends sufficiently far onto the body portion of the driving finger to hold both ends of the bearing face against displacement. A cut-out portion is provided in 50 the cap 27 so that the arms 13 will contact

with the bearing face. The cap 27 fits over the top of the driving finger 14, and the end of the cap will rest against the top of the driving finger to hold the cap in position.

55 I have found that a bearing surface of 70 rubber, leather, or like material, will greatly outwear a steel bearing surface in a device of this kind. When the bearing surface 25 eventually becomes worn it may be replaced, in a manner which will be readily understood 75 from the above description, and there is no necessity for buying a complete new driving finger.

80 While I have illustrated the preferred embodiment of my invention, various changes and modifications may be made in the details of construction without departing from the spirit of the appended claims.

85 What I claim is:

1. A torque attachment driving finger for 85 a lens grinding machine including a body portion with a cut-out section in a face thereof; a replaceable bearing member inserted in said cut-out section to provide a wearing face for the driving finger; and a sleeve formed to 90 fit over a part of the driving finger and bearing member for securing the bearing member to the body portion; said bearing member being constructed of soft material so that the grinding machine will operate with less noise 95 than when operating with an unsurfaced driving finger.

2. A lens grinding machine including in combination a pair of driving fingers; means 100 securing the driving fingers to a driven member; a lens block holder; a driven arm connected to the lens block holder and extending between the driving fingers; bearing faces of soft material mounted on the driving fingers in position to contact with the driving arm 105 whereby the driving fingers will operate the driven arm with less noise than the unsurfaced finger; and means, formed to slide over a portion of the driving fingers and removable 110 and replaceable while the driving fingers are 115 in operative position, for holding the bearing faces in position on the driving fingers.

3. As an article of manufacture a driving finger for grinding machines including a body portion having a cut-out section; a bearing member of soft tough material inserted in the cut-out section to provide a wearing face for the driving finger whereby the grinding machine will operate with less noise than when operated with the unsurfaced driving finger; 120 and retaining means formed to slide over a part of the body portion and of the bearing member for holding a bearing member in place.

4. As an article of manufacture a driving 125 finger for grinding machines including a body portion having a cut-out section; a bearing member of soft tough material inserted in the cut-out section to provide a wearing face for the driving finger whereby the grinding ma- 130

chine will operate with less noise and the wearing face last longer than when operated with the unsurfaced driving finger; and a sleeve formed to fit over the driving finger and provided with a cut-out portion exposing that part of the bearing member which serves as the wearing face.

In testimony whereof, I have hereunto signed my name, at Syracuse, in the county of Onondaga, and State of New York, this 29th day of May, 1930.

HAROLD C. ST. DENNIS.
